UNITED STATES PATENT OFFICE

152,817

DESIGN FOR A COIN OPERATED AMUSEMENT MACHINE OR THE LIKE

Emery Mihalek, Chicago, Ill., assignor to O. D. Jennings & Company, Chicago, Ill., a corporation of Illinois

Application August 16, 1947, Serial No. 140,919

Term of patent 14 years

(Cl. D52—3)

To all whom it may concern:

Be it known that I, Emery Mihalek, a citizen of the United States, residing at Chicago, county of Cook, and State of Illinois, have invented a new, original, and ornamental Design for Coin Operated Amusement Machine or the like, of which the following is a specification, reference being had to the accompanying drawing, forming a part thereof, in which—

Fig. 1 is a perspective view of a coin operated amusement machine or the like, showing my new design;

Fig. 2 is a top plan view thereof;

Fig. 3 is a front elevational view thereof;

Fig. 4 is a side elevational view thereof.

The dominant features of my design reside in the portions shown in solid lines.

I claim:

The ornamental design for a coin operated amusement machine or the like, as shown and described.

EMERY MIHALEK.
